(57) **CLAIM**

The ornamental design for a lamp, as shown and described.

DESCRIPTION

FIG. 1 illustrates a perspective view of the lamp;

FIG. 2 illustrates a rear side view thereof;

FIG. 3 illustrates a front view thereof;

FIG. 4 illustrates a left view thereof;

FIG. 5 illustrates a right side view thereof;

FIG. 6 illustrates a top view thereof; and,

FIG. 7 illustrates a bottom view thereof.

The broken lines illustrate portions of the lamp which form no part of the claimed design.
